UNITED STATES PATENT OFFICE.

CARL AXEL THEODOR SJÖGREN, OF STOCKHOLM, SWEDEN.

GUN.

No. 808,118.

Specification of Letters Patent.

Patented Dec. 26, 1905.

Application filed June 27, 1903. Serial No. 163,323.

To all whom it may concern:

Be it known that I, CARL AXEL THEODOR SJÖGREN, a subject of the King of Sweden and Norway, and a resident of Stockholm, Sweden, have invented a new and useful Improvement in Guns, of which the following is a specification, reference being had to the accompanying drawings, forming a part hereof.

This invention relates to improvements in guns, and more especially to that class of guns which are described in my United States Letters Patent No. 739,732, dated September 22, 1903.

The object of the present invention is to reduce the dimensions of the weights by reducing the work to be performed by the same in their backward movements.

The invention consists, briefly, in the provision of suitable means for compressing in the forward motion of the weight or weights the spring or springs actuating the firing-pin, whereby the spring or springs adapted to throw the weight or weights backward may be made much weaker than before.

In the accompanying drawings I have shown a way of carrying out the invention.

Figure 1 shows a longitudinal section of a part of a gun embodying my invention. Fig. 2 shows a plan view, partly in horizontal section, of the same; and Fig. 3 shows likewise a plan view, partly in horizontal section, with the breech-block in open position.

The weight 1 is movable on the breech-block 2 in the same manner as described in my above-mentioned Letters Patent No. 739,732. In a boring 3 in the said weight are provided two (or more) springs 4 and 5, of which the one, (or more,) 4, is adapted to throw the weight backward after the recoil has ceased, while the other, (or others,) 5, constitutes the spring actuating the firing-pin. The said spring 4 bears at the one end against the bottom of the said boring 3 and at the other end against a shoulder 6 on the breech-block, while the spring 5 for actuating the firing-pin is arranged between the said bottom and the head 7 of the firing-pin 8. The said weight 1 engages, by means of a pin 10, preferably actuated by a spring 9, with two horizontally-turnable angle-levers 11, which are mounted on the breech-block 2 and the fore ends of which are formed as hooks 12, adapted to engage corresponding hooks 13 on a part 15, rigidly connected to the barrel when the breech-block is in its closed position, as shown in Fig. 2. The rear ends of the said

angle-levers are close to each other in the said position of the breech-block and can never be turned so far from each other as to let through the said pin 10, inasmuch as the same when 60 they are turned by the pin in the backward movement of the weight will strike inclined surfaces 16 of the breech-block, limiting the movement of the said angle-levers. The weight 1 will thus in its backward movement 65 first disengage the angle-levers from the hooks 13 and thereupon by means of the said angle-levers throw the breech-block backward. To the rear end of the breech-block is pivotally fixed a sear 17, which is actuated by a 70 spring 18 and when the weight has accomplished its forward motion will engage a hook-shaped recess 19 in the firing-pin in order to keep the spring 5 in compressed condition. For the purpose of firing the gun the said sear 75 17 may be disengaged from the firing-pin by means of a hook 21, pivotally connected to the trigger 20, whereby the firing-pin in the usual manner is thrown forward by the spring 5. 80

The spring 22, which in the form shown in the drawings is adapted to bring the breech-block back into closed position, is arranged in the stock and connected to the weight 1 by means of a fork 23. The backward movement of the weight and the breech-block is limited by a block 24, which in order to facilitate the removal of the breech-block from its guide 25 may be arranged movably up and down and be actuated by a spring 26, 90 which tends to keep the said block in its uppermost position. The hole in which the block 24 is arranged is wider at its lower end, so that the said block when it has been fully forced down into the said hole may be rocked 95 somewhat backward and brought into engagement with shoulders 27, formed in the sides of the guide 25 and adapted to keep the said block 24 in its lowest position.

The arrangements described above work 100 in the following manner: When the different parts are in the positions shown in Fig. 1, in which the gun is ready for firing, and the trigger is operated in the usual manner, the hook 21 will bring the sear 17 out of engagement with the firing-pin 8, which will then be thrown forward and cause firing in the usual manner. The gun now recoils and the weight 1 moves forward, whereby the springs 4 and 5 will be compressed. Since the weight 1 in 110 the forward motion of the firing-pin has a certain tendency to move backward, it is

suitable to have the said sear 17 when it is drawn down by the hook 21 enter a recess 28 in the bottom of the guide 25, so as to prevent a premature backward motion of the weight. In order that the sear 17 in the forward motion of the weight may be able to engage the hook-shaped recess 19 of the firing-pin 8, it is necessary to disengage the said sear 17 from the hook 21. For this purpose the sear 17 is extended downward and bears against the said hook 21 by a plan surface of comparatively great extension in vertical direction, by means of which the hook 21 in the forward movement of the weight 15 will rotate the last-mentioned hook, so as to release the same, whereupon the sear 17 by the action of the spring 18 will engage the hook-shaped recess 19 of the firing-pin. When the recoil has ceased, the spring 4 will 20 throw the weight backward, whereby the pin 10 will first disengage the angle-levers 11 from the hooks 13 and thereupon bring the breech-block 2 backward until the weight strikes the block 24. The withdrawal of the 25 emptied cartridge and the introduction of a new cartridge into the barrel may be performed in any well-known manner and form no part of the present invention. As soon as the weight 1 has struck the block 24 it will 30 be brought back into the position shown in Figs. 1 and 2 by means of the spring 22, whereby also the breech-block 2 will be returned to its initial closed position and the hooks 12 of the angle-levers 11 will again be 35 thrown into engagement with the hooks 13 by means of the spring 4, the fore end of which for this purpose bears against the rear ends of the said angle-levers 12, as clearly shown in Fig. 1. The gun is thereupon ready 40 for new firing. It is only necessary to release the trigger a moment, so as to give the hook 21 opportunity to reengage the sear 17.

Obviously I do not limit myself to the exact form described above and illustrated in 45 the accompanying drawings, inasmuch as the spring or springs actuating the firing-pin may be arranged in any other manner and any other means for compressing the same by

the weight in its forward movement may be used, as easily understood by those skilled in 50 the art.

Having now described my invention and in what manner the same may be performed, what I claim as new, and desire to secure by Letters Patent, is—

55

1. The combination with a gun, of a longitudinally-reciprocating breech-block, a movable weight on the said breech-block adapted to move forward on account of its inertia when the gun recoils, a spring between the 60 said weight and the breech-block adapted to be compressed when the former moves forward and to throw the said weight backward when the recoil ceases, a firing-pin, a firing-pin spring adapted to be compressed by the 65 said weight in its forward movement, means for locking the breech-block in closed position, and means for unlocking the breech-block, substantially as and for the purpose set forth.

70

2. In a gun the combination of a longitudinally-reciprocating breech-block, a weight mounted thereon capable of independent longitudinal movement and adapted to move forward by its inertia and the recoil of the 75 gun when fired, a reaction-spring between said weight and the breech-block, a firing-pin and firing-pin spring within the breech-block, said spring also having bearing against the weight, whereby when the weight moves forward the spring will be compressed, a sear for the firing-pin, hooks mounted on the breech-block to engage coacting hooks or shoulders on the barrel, and a projection on the weight to engage said hooks on the breech-block and release the same when the weight moves back under the influence of its reaction-spring.

80

In testimony whereof I have signed my name to this specification in the presence of 90 two subscribing witnesses.

CARL AXEL THEODOR SJÖGREN.
